(57) **CLAIM**

We claim the ornamental design for a lint catcher, as shown and described.

DESCRIPTION

FIG. 1 is a perspective view of a lint catcher, embodying our new design;

FIG. 2 is a first end elevation view thereof;

FIG. 3 is a second end elevation view thereof;

FIG. 4 is a first side elevation view thereof;

FIG. 5 is a second side elevation view thereof;

FIG. 6 is top plan view thereof; and,

FIG. 7 is a bottom plan view thereof.

The broken lines shown in the drawings illustrate portions of the lint catcher that form no part the claimed design.
